COMPUTING AND LIKE MACHINE

Arthur W. Felertag, Cincinnati, Ohio, assignor to
Remington Rand Inc., New York, N. Y., a cor-
poration of Delaware

Application June 11, 1935, Serial No. 26,047

1 Claim. (Cl. 197—132)

My invention relates to tally roll mechanism for use on computing, tabulating, typewriting and like machines.

One of the main objects of my invention, generally stated, is to provide a simple and efficient automatic rewind device for tally rolls including novel means for controlling the line spacing and feed of a tally roll strip or strips.

Another object of my invention is to provide an improved mechanism of the character specified that may be readily introduced as an attachment to existing computing, typewriting or like machines without modifying, or materially modifying, the existing structural features thereof.

15 A further object of my invention is to provide an improved tally roll mechanism in which a tissue tally strip is used to effect a double printing without the use of carbon paper, and in which the regular ink ribbon is used to produce both first and second copies.

20 Still another object of my invention is to provide improved means for effectively supporting the tally strip take-up roll and yet maintain maximum visibility.

25 A further object of my invention is to provide improved means for line spacing the tally strip and ledger sheet in unison whenever simultaneous spacing of the two sheets is desired.

Another object of my invention is to provide an improved tally roll mechanism which is carried by a fixed part of the machine and does not travel with the carriage.

30 Still another object of my invention is to provide a tally roll mechanism by means of which a duplicate printing of each item may be obtained on a tally strip in a vertical column regardless of the movements of the carriage and the distribution of the same items on the record sheet.

35 A further object of my invention is to provide a tally roll mechanism in which a tally strip is supported and fed independently of the platen and maintained free from contact with the platen and record sheet carried thereby so as not to interfere with the movement of either the carriage or the record sheet.

40 To the above and other ends which will hereinafter appear, my invention consists in the features of construction, arrangements of parts and combinations of devices set forth in the following description and particularly pointed out in the appended claim.

45 In the accompanying drawings, wherein like reference characters indicate corresponding parts in the different views,

Fig. 1 is a right side elevational view, with certain parts omitted, of a computing machine equipped with the devices of my invention;

5 Fig. 2 is an isometric view of a portion of the tally roll mechanism embodying my invention showing said mechanism as a single unit and in normal position detached from the computing machine;

10 Fig. 3 is a vertical sectional view of the device, the section being taken just inside the gears forming the driving train for the take-up roll, on the line 3—3 of Fig. 8 and looking in the direction of the arrows at said line;

15 Fig. 4 is an enlarged, detail fragmentary vertical sectional view taken through the axis of the take-up roll and illustrating the friction drive for said roll, the section being taken on the line 4—4 of Fig. 2 and looking in the direction of the arrows at said line;

20 Fig. 5 is a fragmentary, right side elevational view, with parts in section, of my novel automatic rewind device, the view illustrating the relation of said device to the traveling carriage and certain of the operating mechanism of the computing machine;

25 Fig. 6 is a detail, vertical sectional view through the tally strip chute, the section being taken on the line 6—6 of Fig. 1 and looking in the direction of the arrows at said line;

30 Fig. 7 is a fragmentary, detail, sectional view showing the relative positions of the tally strip, ribbon, ledger sheet, and platen together with the upper part of one of the type sectors; and

35 Fig. 8 is a fragmentary, vertical sectional view through the tally strip feed roll and taken along the line 8—8 of Fig. 5.

40 I have shown my invention in the present instance embodied in a computing machine known as the Dalton "Multiplex" commercial ledger posting and statement machine, model 490 Z-131 Z, in which the devices of my invention may be readily incorporated without modifying, or materially modifying, the existing structural features of such machine. Since the above machine is a well known and marketed computing machine, I have only shown so much thereof as is necessary to arrive at an understanding of my invention in its embodiment therein. It should be understood, however, that the invention is not restricted to its use in said machine alone but may be included in various forms of computing, typewriting and like machines generally, wherever found available.

45 I shall first describe some of the existing structural features of the Dalton "Multiplex" machine

and will afterwards describe the devices of the present invention in their combination therewith.

The Dalton computing machine, as is well known, is a machine of the ten-key type in which the major portion of the mechanism is housed within a casing or cover member 10, as shown in Fig. 1. The keyboard is situated at the front of the casing or machine and includes a set of numeral keys 11, which upon being depressed successively will set up corresponding amounts in the usual pin carriage (not shown), so that upon making an operating stroke of the usual handle 12 said amounts will be entered into the accumulator wheels. Simultaneously with this computation or entering into the accumulator wheels, printing instrumentalities or type sectors 13 will be swung upwardly to position to print the amount upon any suitable record sheet R through the medium of an interposed ink ribbon 14 fed from one to the other of the usual ribbon spools 15 suitably mounted toward the front of the machine on the upper side of the casing 10.

During each printing operation the types strike against a platen 16 around which the sheet R has been fed in a manner to be presently described, said platen having a shaft 17 which is journaled in suitable bearings provided in end plates 18 and 19 of the usual traveling carriage which is designated as a whole by the reference numeral 20. As shown in Fig. 5 the carriage 20 is of the usual construction and is provided with grooved raceways in rails 21 thereof in which anti-friction rollers or balls 22 are received, said balls also being received in oppositely disposed grooved raceways 23 of a fixed supporting bar or rail 24. The carriage is thus supported for traveling movement from side to side of the machine and relatively to the printing instrumentalities 13.

40 The usual means are employed for propelling the carriage and arresting it in its different columnar positions for the entry of items in the different columnar fields on a work sheet or sheets carried by the carriage. The usual means are also employed for "normalizing" the machine and thereby preventing tabulating jumping of the carriage where the entries are to be made vertically instead of horizontally on the ledger sheet, as will hereinafter appear. However, inasmuch 45 as a showing of such "normalizing" means is unnecessary to arrive at an understanding of my present invention, illustration thereof has been omitted.

To aid in the handling and insertion of work sheets into the machine there is provided a paper table 25, paper rest plate 25^a and paper guides 26, said paper table being carried by the carriage and secured between the side plates 18 and 19 thereof by shoulder screws 25^b. The paper rest plate 25^a is adjustably secured to and supported by the paper guides 26 with the aid of knurled screws 26^c. The paper guides 26 have forwardly projecting flanges 26^b at the sides thereof which constitute side edge guides for determining the lateral position of the ledger sheet or record sheet on the carriage, and are supported by arms 27 which are adjustably mounted on the square shaft 26^c. An additional guide 28 aids in leading a record sheet to the rear side of the platen where feed rollers 29 and 30 coact with the platen 16 in a well known manner, and the usual paper deflector 31 will lead said sheets to the printing point or line when the platen shaft 17 is turned. 70 The feed rollers 29 and 30 are of the usual re-

leasable construction, being spring pressed against the platen, thereby holding the inserted work sheet against the platen to effect a feed thereof.

According to the type of work that is being 5 done on the machine at any given time, a group of entries to be made on a record sheet may be entered in a horizontal line by tabulating the carriage from one column to another in the usual manner. At times, however, the character of the 10 work may be such that it is deemed desirable to make the group of entries on the record sheet in a vertical column one under another instead of across the sheet. In order that this may be accomplished, the model of the Dalton machine 15 hereinbefore referred to is provided with a finger piece or button (not shown) on the front plate of the machine for "normalizing" the operation 20 of the machine. This button when in one position causes the carriage to be advanced or stepped forward at each actuation of the handle 12 to a new columnar field or tabulated position, in order that the entries may be made in a horizontal line across the sheet. When, however, this button is in the other or "normalizing" position 25 it will cut out the tabulating operation of the carriage at each actuation of the handle, so that the carriage remains at rest, but at each such operation of the operating handle will cause 30 the line spacing mechanism to be actuated in order to print the items one under another in a vertical column.

In the present instance, I have shown only so much of the mechanism referred to above as is necessary to arrive at an understanding of the 35 same in its cooperation with the devices of my invention. Referring to Fig. 5 it will be seen that a depending arm 32, which is held in a central position in the machine by attachment in a well known manner to the fixed rail 24, extends into 40 the body of the machine. This arm 32 is provided with a roller 33 at the lower end thereof which is adapted to cooperate with an actuating member 34 in the machine, said actuating member 34 being given a forward or clockwise movement during the downward stroke of the operating handle 12 and being returned to normal position, shown in Fig. 5, during the latter part of the return stroke of the operating handle. Due to the coaction between said member 34 and the roller 33, the arm 32 will be given a corresponding oscillatory movement at each actuation of the handle of the machine, provided that the button hereinbefore referred to is set in "normalizing" position. The effect of operating the arm 32 in this manner is to rock a universal rock shaft 35 with which said arm has an operative sliding connection, said shaft 35 being mounted to turn in bearings in the end plates 18 and 19 of the carriage and at its ends extending beyond said 50 plates.

Secured to the right-hand end of the shaft 35, as shown in Fig. 1, is a crank arm 36 having pivoted thereto at 37 a line spacing pawl 38. A contractile spring 39 is connected at one end to the pawl and at its opposite end to the crank arm 36 and thus tends to urge the pawl 38 in a clockwise direction about its pivot 37 and into engagement with a ratchet wheel 40 mounted on the platen shaft 17. A stop lug 41 projects laterally from the pawl 38 and underlies and coacts with the forward end portion of the arm 36 to limit the relative movement between the pawl and its carrying arm in one direction and under the force of the spring 39. Thus, during 70 75

each oscillation of the arm 32 the crank arm 36 will first be given an upward movement carrying the pawl 33 against the wheel 40 and stressing the spring 39. After reaching an extreme 5 position in this direction the arm 36 will be returned to normal position and advance the platen one line space, after which the pawl will be disengaged from the ratchet wheel 40, leaving the parts in the normal position shown in Fig. 1 10 ready for the next operation.

From the foregoing description, it will be apparent that if desired, the platen 16 can be line spaced at each actuation of the operating handle 12 when the "normalizing" button is in position 15 to cut out the tabulating operation of the carriage.

Having described briefly certain of the features 20 of the Dalton computing machine, I shall now describe the devices of my invention as they may be combined therewith.

In machines of the same general character as the Dalton in which the devices of my present invention have been embodied, due to the fact 25 that a traveling carriage is employed so that entries may be made in a horizontal line across a work sheet when desired, duplicate copies are usually obtained in the ordinary manner by using a second work sheet with a carbon sheet or auxiliary ribbon carried by the carriage and interposed between the sheets. When tally roll mechanism is employed it is usually mounted on the carriage to travel therewith and hence is set to 30 take duplicate entries of certain columns only, the tally strip being wrapped around the platen 35 with the record sheet.

According to my present invention I provide 40 tally roll mechanism that is carried by a fixed part or parts of the machine and does not travel with the carriage. Hence, the record sheet R carried by the carriage will move relatively to the tally strip, and obviously such a tally strip cannot be wrapped around the platen and cannot interfere with the traveling movement thereof. However with tally roll mechanism of my present 45 invention I am enabled to effect a duplicate printing in a vertical column on the tally strip of every item entered, regardless of the movements of the carriage and the manner of distributing the same items on the record sheet 50 carried thereby, and without interfering with the travel of the carriage and the work sheet which is carried by it.

Furthermore, according to my present invention I aim to eliminate the use of any interposed 55 carbon sheet or auxiliary ribbon by employing a thin tissue tally strip of a transparent or translucent texture which will be fed in front of the regular inked ribbon 14, so that when the type 60 are moved to printing position, in addition to the usual imprint being formed on the front side of a record sheet, an imprint will also be made upon the rear side of the tissue tally strip. Since the tally strip is of a transparent or translucent 65 character the imprint may be read or inspected from the front side thereof. Such a method of printing on the rear side of a strip or sheet is known as "ghost" printing and, as mentioned above, eliminates the use of a carbon sheet or 70 auxiliary ribbon and produces a regular inked duplicate copy.

In addition to the above, I aim to provide this mechanism for effecting "ghost" printing on a tally strip, which may be applied as an attachment 75 to the regular Dalton computing machine

described above; and provide, in conjunction therewith, mechanism by means of which the tally strip may be rewound on a separate roll at the front of the machine, the tally strip being fed to said roll in single line spacing movements 5 upon each actuation of the operating handle 12.

Referring again to Fig. 1, it will be seen that I have provided at the rear of the machine a tally strip supply roll 44 which is supported by brackets 45 secured by screws 46 to the rear of the casing 10. From the supply roll 44 a tissue tally strip T may be fed into a chute or guide 47. As shown in Fig. 6 this chute 47 may be formed of two thin strips of metal or other suitable material which constitute upper and lower cover members 48 and are held apart by means of two separating strips 49. The cover members 48 and separators 49 may be secured together in any desirable manner, such as by welding, to thereby form the closed chute 47, having an internal opening or passage way 50 of sufficient size to allow the tissue tally strip T to pass through.

It is the purpose of the closed chute 47 to lead the tissue tally strip T from the supply roll 44 over the rear portion of the machine and beneath the carriage 20 and platen without interfering therewith, and thence upward to the printing line. Therefore, in order that the tally strip T may arrive at the printing line in a clean and undamaged condition, it is desirable to 30 mount the chute 47 upon the machine in such a manner that there will be no sharp curves or cutting edges to mutilate the tissue strip when it is being drawn through said chute. Accordingly, as indicated in Fig. 1, I provide an upwardly bent lip or flange 51 at the opening end of the chute 47 adjacent the supply roll 44 to aid in the insertion of the tally strip T into said chute and prevent said strip from being torn during feeding. At the rear of the machine the 35 chute 47 is supported by means of posts 52 and may be secured to the top of the casing 10 at any convenient points and in any suitable manner, such as with the aid of screws 53. Thus, said chute 47 passes over the rear portion of the machine in a substantially horizontal plane, is then bent downward with as wide a curve as possible and led beneath the carriage and platen, as shown in Figs. 1 and 5, from where it passes upward in front of the type sectors 13. Upon approaching the printing line position, as indicated in Fig. 7, the chute passes in front of the printing ribbon 14 and terminates just above said ribbon. Obviously, such a manner of mounting the tally supply roll and leading it to the printing line position will in no way interfere with the movement of the carriage or the record sheet 40 carried thereby.

Referring now to Fig. 2 it will be seen that the chute 47 is provided with a substantially rectangular cut-out portion at the upper end thereof. This cut-out portion 54 is deep enough to allow the tissue tally strip T to be exposed to the action of the types at the printing line and thereby receive imprints on the rearward side thereof during the printing operation of the types. However, the cut-out portion 54 is slightly less in width than the width of the tissue tally strip T and thus forms marginal engaging and holding portions 55 for said tally strip. It will be 50 apparent that these holding portions 55 constitute supports for the tally strip and maintain it in a rigid and vertical position at the printing line thereby facilitating in the production of clear and well defined imprints on said strip and 55

still hold the tally strip out of the path of movement of the carriage.

After being led from the supply roll 44 through the chute 47 to the printing line the tissue tally strip passes upward to my improved automatic feeding and rewinding mechanism which will now be described.

Referring particularly to Figs. 1, 2 and 5 it will be seen that my automatic feed and rewind device, which is designated as a whole by the reference numeral 56, comprises left and right side plates or frame members 57 and 58 (Fig. 2) supported and maintained spaced apart by means of suitable forward and rear guide rods or cross bars 59 and 60 respectively. This frame is mounted at the front of the machine, forward of the carriage and directly over and forward of the type sectors 13, by means of foot pieces 61 and conveniently secured to a part of the casing with the aid of screws 62. As shown in Fig. 5 the screws 62 are fastened into downwardly projecting ears 63 provided on an auxiliary hood-shaped casing member 64 which covers that part of the actuating mechanism projecting above the main casing 10.

From an inspection of Fig. 2, which shows the parts in normal position though detached from the machine, it will be seen that a bail, comprising rearwardly projecting arms 65 and 66 pivoted at 67 and 68 to the side plates 57 and 58 respectively and connected at their rearward end by means of a cross bar 69, forms a support for a paper cutter 70 which is secured to said cross bar 69 by means of screws 71. A finger piece 68a is provided on the arm 66 adjacent the pivot 68 for the purpose of manually raising the bail as will hereinafter appear. Mounted on a shaft 72 which is journaled in the arms 65 and 66 at the ends thereof and below the cross bar 69, is a feed roll 73. A spring 74 attached at one end to the arm 65 and at its other end to the side plate 57, tends to turn the bail 65, 66, 69 in a counter-clockwise direction (as the parts appear in Fig. 3) about its pivots 67 and 68 and move the feed roller 73 into engagement with a second cooperating feed roller 75, by and between which feed rollers the tally strip is fed. The feed roll 75 is mounted upon a shaft 76 which is given a constant and definite feeding or line spacing movement with every actuation of the operating handle 12, as will hereinafter more clearly appear.

I shall now describe the means by which the above mentioned line spacing movements of the feed roll 75 are effected.

As the parts are shown in Fig. 8 the shaft 76 terminates at the right-hand end thereof in a reduced portion 77 which is journaled in the side plate 58. If desired a washer 78 may be provided on the inside of the side plate 58 to reduce the end friction of the shaft 76 against said plate. Likewise the opposite end of the shaft 76 terminates in two progressively reduced portions 79 and 80 respectively, the former being rotatably mounted within a hub 81 which is fixed in the side plate 57. On the inside of the side plate 57 a driving gear 82 is fixed to the reduced portion 79 of the shaft 76 for rotation therewith by means of a pin 83. This gear 82 is used to drive a paper wind-up reel as will hereinafter more clearly appear.

A second hub 84 is mounted on the reduced portion 80 of the shaft 76 and secured thereto by means of a set-screw 85. This hub 84 has a ratchet wheel 86 fixed to the end thereof adjacent the hub 81 and at the opposite end thereof is

provided with a knurled knob 87 so that the feed roll 75 may be rotated by hand if desired. The teeth 86a of the ratchet wheel 86 are adapted to cooperate with a feed pawl 88 which is pivoted at 89 to an arm 90 as shown in Figs. 2 and 5, said arm 90 being fixed upon a hub 91 which is rotatably mounted on the fixed hub 81. Thus, regardless of the movements of the shaft 76 the arm 90 may be moved as desired. As best shown in Fig. 5 the pawl 88 is held in constant engagement with the teeth 86a of the ratchet wheel by means of a spring 92 which is attached at one end to the pawl and at its other end to the arm 90, while a stop pin 93 limits the movement of the pawl 88 in the opposite direction.

Pivottally connected to the arm 90 at 94 and extending downwardly therefrom is a link 95 which is pivotally connected at its lower end at 96 to a lever arm 97. The lever arm 97 constitutes one arm of a bell crank or actuating lever 98 which is pivotally mounted upon a pivot stud 100. The other arm 101 of said actuating lever 98 extends downwardly into the machine at a position in front of a roller 102 provided on the upper end of the usual right-hand hammer restoring arm 103 which insures a proper operation and return of the printing hammers 103a. This arm 101 is held in constant engagement with the roller 102 by means of a spring 104, which is attached at one end to a pin 105 provided in said arm, and at its other end is attached to a pin 106 provided in a downwardly extending projection 107 of the guide plate 57. Thus, the arm 101 is held in normal position by the hammer restoring arm 103 and will follow the movement of said arm as will presently appear.

In the Dalton machine with each downward stroke of the operating handle 12 the hammer restoring arm 103 will move toward the rear of the machine or to the right as shown in Fig. 5, and on the upward or return stroke of said operating handle the restoring arm 103 will be returned to its normal position shown in Fig. 5. It will be apparent that during such movement of the hammer restoring arm 103, the arm 97 of 45 said actuating lever 98 will first be moved upward and then will be returned to its normal position. Such movement of the arm 97 of the actuating lever will transmit an oscillatory motion to the pawl carrying arm 90 whereby said arm will first be moved in a clockwise direction, as the parts are shown in Fig. 5, and will then be moved in a counter-clockwise direction back to normal position. This will cause the pawl 88 to first move back over the teeth 86a of the ratchet wheel 86 so that on the forward or counter-clockwise movement of the pawl carrying arm 90 the feed roller 75 will be turned in a line spacing direction. As shown in Figs. 2 and 5, the arm 97 is limited in its upward movement by a stop pin 108 and limited in its downward movement by a similar pin 109 provided in the side plate 57. A spring detent 110 pivoted at 111 to the side plate 57 may be provided to engage the ratchet wheel 86 and prevent accidental displacement or advance thereof in the usual manner. It is to be understood that the construction and arrangement of the above described line spacing mechanism for the feed roller 75 is such that upon a return stroke of the operating handle 12 said feed roll will be rotated a distance sufficient to advance any sheet or strip fed between said roll 75 and the feed roll 73 a distance of one line space.

Therefore, when the tissue tally strip T is fed

by and between the feed rolls 73 and 75, it always will be advanced the same uniform distance of one line space upon each actuation of the operating handle 12. When fed in this manner, the finished or typed tally strip T may, if desired, be torn off with the aid of the cutting knife 70. In addition to the automatic feed of the tissue tally strip, said strip may be fed by hand either by turning the knurled knob 87 or by releasing the upper feed roll 73 with the aid of the finger piece 68^a provided on the lever 66 and pulling the strip T up manually. If desired, the tissue tally strip T may be guided in its movement from the chute 47 to the feed rolls 73, 75 by providing guide flanges 112 on the cross bar 59, as shown in Fig. 2.

It will be recalled that as described above, when the "normalizing" button is set in "normalizing" position the platen 16 may be rotated upon each actuation of the operating handle 12 to feed the record sheet R a line space distance upon each such actuation. Therefore, when said button is in the "normalizing" position the tally strip and ledger sheet may be line spaced in unison and equal distances.

In addition to the means for automatically feeding the tally strip in line spacing direction upon each actuation of the operating handle 12, I have provided auxiliary means for winding said tally strip upon a reel or spool as said strip is fed from the feed rolls 73 and 75. I shall now describe the automatic winding mechanism.

Referring particularly to Figs. 2 and 4 it will be seen that I have provided a tally strip rewind reel or spool 115 for receiving and winding thereon the tissue tally strip T as it is fed from the feed rolls 73 and 75. The rewind spool per se may, for the purposes of the present invention, be of any suitable construction though that shown in the present instance is of the type disclosed in the application of Norbert A. Jung, filed June 11, 1935 and bearing Serial No. 26,063 which matured as Patent No. 2,059,242 on Nov. 3, 1936 which, for the purpose of clamping or attaching a tally strip thereto, is provided with a special core 116 that may be separated and closed by means of a push-rod 117 having a finger button 118 at the right-hand end thereof. The push-rod 117 serves as a shaft for the spool 115 at the right side thereof and is received in a hub 119 provided at the upper forward portion of the side plate 58. At the left-hand end of the spool 115 and in axial alignment with the push-rod 117 there is a shaft portion 120 fixed to the left-hand portion of the spool and having a bearing flange 121 adjacent its point of attachment to said spool. The shaft portion 120 is received in a hub or friction member 122 having a bearing flange 123 at the right-hand end thereof inside the side plate 57, said friction member 122 being in turn received or journaled in a hub 124 provided in the side plate 57. A gear 125, which constitutes a driven gear, is loosely mounted on the shaft portion 120 inside the side plate 57 and between the bearing flanges 123 and 121 shown in Fig. 4 and meshes with an idler gear 126 (Figs. 3 and 5) which is pivoted to the side plate 57 by means of a headed pivot pin 127. The idler gear 126 also meshes with the driving gear 82 provided on the shaft of the feed roll 75 which, as described above, is given a line spacing movement with each actuation of the operating handle 12. Therefore, the driven gear 125 on the spool shaft portion 120 will be advanced due to the intermeshing idler gear 126.

If the gear 125 were fixed on the shaft portion

120 of the spool 115, said spool 115 would be rotated a corresponding extent each time the feed roll 75 was given a line spacing movement due to actuation of the operating handle 12. However, a positive connection between the winding spool 115 and the rotating mechanism of the feed roll 75 is not desired since it would result in a tearing of the tally strip T because of increasing tension in said strip due to the increasing diameter thereof as it is wound on the core 116. That is, if the rewind roll reel 115 were rotated a constant amount at each actuation of the operating handle 12, as the tally strip T was wound thereon, said strip T would be advanced a greater distance by rotation of the spool 115 than it had been fed uniformly due to the action of the feed rolls 73 and 75. It will be apparent, therefore, that if the pressure between the feed rolls 73 and 75 is too great it will effect a tearing of the tally strip T; whereas, if the tally strip is pulled through between the feed rolls 73 and 75 without tearing, it will result in an improper spacing of the items as they are entered upon said strip. Hence, by my present invention I do not fix the gear 125 upon the spool shaft portion 120 but provide an automatically controlled friction drive or connection between said gear and the spool 115.

As shown in Fig. 4 and described above, the gear 125 is loosely mounted on the shaft portion 120 between the friction bearing flanges 123 and 121. The shaft portion 120 projects to the left beyond the extremities of the hubs 122 and 124 and has secured at the end thereof a hollow cap or housing member 130. This member 130 is secured to the shaft portion 120 by means of a headed screw 128 received in a tapped opening 129 in the end of the shaft portion 120. Surrounding the shaft portion 120 and within the hollow cap 130 is a contractile expansion spring 131 which bears at the inner end thereof against the end of the hub 122 and at its opposite end bears against the inner end wall of said cap 130. The tension of the spring 131 is great enough to push the hub 122 inwardly to cause a frictional engagement between the gear 125 and the friction flanges 123 and 121 and thereby effect a rotation of the spool 115 when the feed roll 75 is turned to wind the tally strip T upon the core 116. However, the frictional engagement of the gear 125 is such that as the tension in the tally strip increases due to the increase in the diameter of the spool with the winding of the tally strip thereon, parts of the frictional driving connection between said gear and the spool will slip one on another before the strip can be drawn between the feed rollers or torn. Thus, by providing an automatic frictionally controlled connection between the driven gear and the spool, I am enabled to prevent a mutilation of the tally strip T or too great a feed thereof, the amount of feed of said tally strip always being governed by the feeding means.

It will be understood that when the screw 128 is drawn up tightly, manual turning of the cap 130 will effect a rotation of the entire rewind spool so that the tally strip may be wound or unwound by hand when desired.

From the foregoing description it will be understood that I have provided:

(1) Tally roll mechanism which is carried by a fixed part of the machine and does not travel with the carriage;

(2) Tally roll mechanism by means of which a duplicate printing of each item may be made

on a tally strip in a vertical column regardless of the traveling movements of the carriage and the distribution of the same items on the record sheet;

5 (3) Tally roll mechanism in which a tally strip is supported and fed independently of the platen and maintained free from contact with the platen and record sheet carried thereby so as not to interfere with the movement of either the carriage or the record sheet;

10 (4) Simple and efficient means for rewinding a tally strip which includes means for controlling the line spacing and feed of said strip independently of the line spacing of the carriage carried record sheet, though it may be in unison therewith;

15 (5) Tally roll mechanism which is independent of the carriage and may be readily applied as an attachment to existing computing, typewriting or like machines without modifying, or materially modifying, the existing structural features thereof; and

20 (6) Tally roll mechanism in which the tally strip is used to effect a duplicate printing without the use of any auxiliary ribbon or carbon paper.

25 While I have shown with some detail a Dalton machine embodying my invention, it should be

understood that the mechanism of my invention may be embodied in various machines differing widely in character; that parts of the mechanism disclosed may be employed without others and that various changes may be made in such mechanism without departing from my invention as it is defined in the accompanying claim.

5 What I claim as new and desire to secure by Letters Patent is:

10 In a calculating machine, the combination with the printing type and the horizontally movable platen thereof, of a tally strip guiding chute for maintaining a tally strip in fixed horizontal relation to said type in all positions of said platen, automatically operating ratchet operating means, a tally strip feed ratchet operable by said means, a train of gearing operable by said ratchet, a tally strip take-up-spool formed with a shaft portion and a bearing face, said shaft portion forming a 15 bearing for one gear of said train, a sleeve on said shaft portion and formed with a bearing face, a spring, and means operable for tensioning said spring so as to cause said bearing faces to frictionally drive said take-up-spool.
